Atty.

UNITED STATES PATENT OFFICE.

RALPH ST. L. PEVERLEY, OF NEW YORK, N. Y., ASSIGNOR, BY MESNE ASSIGNMENTS, TO STRUCTURAL GYPSUM CORPORATION, OF NEW YORK, N. Y., A CORPORATION OF DELAWARE.

BUILDING CONSTRUCTION.

Application filed June 27, 1921. Serial No. 480,903.

To all whom it may concern:

Be it known that I, RALPH ST. L. PEVERLEY, a citizen of the United States, and a resident of the city, county, and State of New York, have invented an Improvement in Building Construction, of which the following description, in connection with the accompanying drawings, is a specification, like characters on the drawings representing like parts.

This invention relates to a building or like construction and more particularly to the roof and floors thereof.

The invention has for its object to provide a roof or floor composed of individual preformed reinforced slabs of gypsum, concrete and like plastic material and of novel construction, as will be described, with which a roof or floor of the required or desired strength can be obtained with slabs composed of gypsum or like material having relatively little strength in and of itself, and which roof or floor can be erected with the slabs in a wet condition and yet have the roof or floor free from bends or deflections therein and provided with substantially flat or straight surfaces.

To this end, the roof or floor is composed of a plurality of slabs of gypsum or like plastic material having embedded in it a longitudinal reinforcing member for the lower portion of the slab and also having embedded in it a longitudinal strengthening member for the upper portion of the slab, and preferably having side flanges located at the bottom of the slab.

The side flanges of laterally adjacent slabs co-operate to form a close joint between the slabs and thereby form a substantially continuous under surface for the floor or roof, and they also form the bottom wall of a space between the upper portions of the sides of the adjacent slabs to support plastic material used to fill said space and prevent said plastic material passing through the floor or roof between said adjacent slabs. The slabs may be provided with end flanges which rest upon the purlins or other supports and form the bottom wall of a space between the ends of longitudinally adjacent slabs.

The strengthening member may and preferably will be supported at its ends by the longitudinal reinforcing member so as to

form a truss within each slab, and the longitudinal reinforcing member may and preferably will be extended through the end walls of the slab above the end flanges. The slab may be provided with transverse reinforcing members as will be described.

The particular features of the invention will be pointed out in the claim at the end of this specification.

Fig. 1 is a plan of a portion of a roof or floor construction embodying this invention.

Fig. 2, a section of the floor shown in Fig. 1.

Fig. 3, an enlarged section of a portion of the floor shown in Fig. 1, taken on the line 3—3.

Fig. 4, a detail in section on the line 4—4, Fig. 3.

Fig. 5, an end view on a smaller scale of two laterally adjacent slabs shown in Fig. 1.

Fig. 6, a detail in plan of a portion of an end slab, and

Fig. 7, a section on the line 7, Fig. 6.

In the present instance, I have shown a sufficient portion of a floor or roof composed of a plurality of individual preformed or precast slabs *a* to enable the invention to be understood.

The slabs *a* are preferably composed of gypsum or like relatively light plastic material having relatively little strength, and are formed or cast in suitable molds, not shown, to provide the same with relatively narrow side flanges 12, (see Fig. 5) located at the bottom of the slab, and preferably also with end flanges 13.

The slab *a* is provided with longitudinal reinforcing members 16 for the lower portion of the slab and with strengthening members 21 for the upper portion of the slab.

The longitudinal reinforcement comprises, as shown, a plurality of metal rods or wires 16, which may and preferably will be inclined upwardly in opposite directions from near the center of the slab, and may and preferably will be made of sufficient length to extend through the end walls of the slab above the end flanges 13.

The strengthening members 21 for the upper portion of the slab may and preferably will be made of sheet metal and bent into substantially *U*-shape to straddle the

reinforcing member 16 and be supported at its ends by said reinforcing member, and thus form therewith a truss within the slab.

The slab *a* may be provided with transverse reinforcing members, comprising a member 14 located near the longitudinal center of the slab and co-operating with the longitudinal reinforcing member 16 to place the latter under tension and to restrain it 10 against upward displacement, and members 15 located upon the end flanges 13 and bonded therewith.

The preformed reinforced slabs *a* are erected upon the building with the end flanges 13 of longitudinally adjacent slabs resting on purlins or other supports 18 and preferably abutting to form the bottom wall of a space 19, and with the side flanges 12 abutting and forming the bottom wall of a space 20 between the upper portion of the sides of the laterally adjacent slabs.

It will be observed that the space 20 extends across the span between the purlins or supports 18, and is closed by the bottom wall 25 formed by the abutting side flanges 12, thereby preventing waste of plastic material 25 (see Fig. 5) employed to fill said space to provide the floor with a continuous upper surface, and also avoiding damage by the 30 plastic material passing through the floor, in the absence of said side flanges.

The strengthening member 21 materially strengthens the upper portion of the slab and is especially valuable when the slab is made 35 of gypsum or like relatively weak material as it increases the resistance of the slab to compressive stresses placed upon it to such extent that the slab can be used substantially as soon as poured or cast and while 40 in a very wet condition, without danger of the slab bending or buckling, and conse-

quently without danger of forming other than a flat or straight floor or roof, and the value of the strengthening member continues and adds great strength to the gypsum slab 45 when the latter is dry and completely hardened.

The longitudinal reinforcing members 16 of adjacent slabs may and preferably will interlock in the spaces 19 before the plastic material 22 is filled in, and thereby provide 50 the floor or roof with a continuous reinforcing member.

It will be understood that the longitudinal reinforcing members 16 of what may be termed the end slabs *a* are anchored at one end in any suitable manner, and in Figs. 6 and 7, I have illustrated one method of anchoring, which consists in bending the reinforcing member 16 around a transverse reinforcing member 23 before the plastic material is poured or cast, so that when the said material is cast or poured into the mold, the anchoring member 23 will be embedded 55 in the plastic material.

Claim:

A preformed reinforced slab comprising a slab of plastic material provided with side flanges located at the bottom of said slab, and having embedded in it a longitudinal 70 reinforcing member inclined upwardly from near the center of the slab toward its opposite ends, and having embedded in it a longitudinal strengthening member for the upper portion of the slab which has its opposite ends supported by the inclined portions of the reinforcing member and forms with the latter a truss within said slab. 75

In testimony whereof, I have signed my name to this specification.

RALPH ST. L. PEVERLEY.
